UNITED STATES PATENT OFFICE.

JOHANN RUDOLF SCHMITT, OF FRANKFORT-ON-THE-MAIN, GERMANY,
ASSIGNOR TO MASCHINENFABRIK FÜR TABAKINDUSTRIE GESELL-
SCHAFT MIT BESCHRÄNKTER HAFTUNG, OF FRANKFORT-ON-THE-
MAIN, GERMANY.

MACHINE FOR THE PRODUCTION OF CHEROOTS.

No. 809,469.

Specification of Letters Patent.

Patented Jan. 9, 1906.

Application filed January 11, 1905. Serial No. 240,601.

To all whom it may concern:

Be it known that I, JOHANN RUDOLF SCHMITT, a subject of the German Emperor, residing at Frankfort-on-the-Main, Germany, have invented a certain new and useful Improvement in Machines for the Production of Cheroots, of which the following is a specification.

This invention relates to a machine for the production of cheroots and the like wherein in successive steps the tobacco which is fed loose to the machine is pressed into shape, provided with a wrapper, and the finished cheroot cut at both ends. To this end the machine is so constructed that first a descending knife cuts off a certain quantity of tobacco, which tobacco is forced by a rammer between two stationary guides against a table. The rammer and the table are formed hollow or concave, corresponding to the shape of the tobacco rolls or bunches to be produced, so that the tobacco is molded into shape on the descent of the rammer. Through an opening in the movable table the roll passes to a loop in the rolling-apron located beneath the mold, and the wrapper is then wound round the bunch by the wrapping device and the rolling-fork operated in the usual way. In order to make the wrapper adhere to the bunch, the wrapper is in its movement over the rolling-table provided with a certain quantity of paste supplied from a vertically - reciprocating container. The cheroot made in this way then passes through a chute to a cutting device comprising a cutting-jaw corresponding to the length of the cheroot and is guided between two stationary side cheeks in order to cut the cheroot at both ends simultaneously.

In the accompanying drawings, which illustrate the invention by way of example, Figure 1 is an elevation, partly in section, showing such parts of the machine as are essential for the steps of the process recited. Figs. 2 and 3 show the container for the paste. Fig. 4 is a transverse section through the press. Fig. 5 is a front view thereof. Fig. 6 is a plan of the table. Fig. 7 shows the cutting device in side elevation. Fig. 8 is a plan thereof. Fig. 9 shows the cam for actuating the rammer. Fig. 10 shows the

cam for moving the vessel containing the paste.

At the one side of the frame 1 of the machine is secured the bracket-arm 2, to which is attached one end of a curved bar 3, which serves as a support for the main shaft 4. The other end of said bar 3 is carried by the bracket 5, which at the same time serves as an axial support for several operating-levers. The arm 6 carries the part 7 of the slideway in which the cheroot is turned through ninety degrees around its longitudinal axis, so that it can slide in axial direction through the chute 8 in front of the cutting device. The latter is mounted in the under bracket 10 of the frame. Beneath the tobacco feedway or channel 11 are the stationary guides 12^a 12^b of the pressing device. In grooves in said cheeks is fitted a table 13, which is concaved or hollowed on its upper face, corresponding to the form of the roll or bunch to be produced. The other half of the mold is formed by concaving the face of the rammer 14, which is reciprocated between the guides 12^a and 12^b. The said rammer is actuated by means of a system of levers 15^a 15^b 15^c 15^d from the main shaft 4, actuated by the cam 16. In front of the end of the tobacco feedway or channel is moved the knife 17, operated in the usual manner. On the other side of the rammer, opposite the feedway, the plate 18 is pivotally attached to a lever 19, and by means of the spring 20 retracted to its original position. The paste vessel consists of the cylindrical vessel 21, with a cylindrical casing 22 at its lower end, the space within which casing is almost entirely occupied by the roller 23. The roller 23 has peripheral grooves, the number of which is equal to the number of teeth of the ratchet-wheel 25 on the same axis 27. The lever 26 is loosely pivoted on the axis 27, and its other end rests on the bolt 28, attached to the frame. The pawl 29 is attached, by means of a pin, to the lever 26 and engages the teeth of the ratchet-wheel 25. The two-armed lever 31, carrying the paste-container, transmits the rotation of the cam 32 to the same. A projecting arm of the bracket 6 forms a support for the rolling-table 33 and the rolling-apron 34. Beneath the outlet of the

mold the table is hollowed, so that the bunch ejected from the mold will fall into the hollow fold or loop of the apron. One end of said apron is secured to the table 33, and the 5 other end runs in the usual way over the pins on the rolling-fork 35 and terminates at the lever 36, which is actuated in any suitable way from the main shaft. Over the apron slides the wrapper-applier 38, attached to a 10 lever 37 and which in the usual way is operated by levers 39^a, 39^b, and 39^c from the main shaft. On the shaft 40, beneath the table 33, the sleeve 41 is slidably arranged, and this sleeve carries on its upper side two pins, 15 one of which effects the connection with the table 13, while the link 42 is secured to the other, which link transmits the oscillating movement of the two-armed lever 43 to the sleeve. The other arm of the lever 43 carries 20 a pin 44, which engages the groove of the drum 45. The table 13 is hollowed or concaved at the forward end of its face, corresponding to the form of the bunch, while it has an opening 13' at its rear end, through 25 which the bunch may fall onto the apron 34.

The cutting device shown in Figs. 7 and 8 consists of the cutting-jaw 46, concaved at its forward end, corresponding to the form of the cheroots and bearing against the bunch. 30 Its breadth is so dimensioned as to correspond with the length of the cheroots to be produced. At the same distance apart the cheeks 47 are secured to the base-plate 48, so that the jaw 46 fits exactly between them. 35 The jaw 46 is rigidly connected with the guide-rail 49, engaged by an arm of the angle-lever 50, pivotal around the axis 51, resting in the bearings 52^a and 52^b, carried on the arm 6. The other member of the lever 50 40 engages the link 53, which is moved by the two-armed lever 54, carried in the bracket 5. The operation of this lever is effected by the cam 55, having a groove 56 entered by a pin on the lever 54. Opposite the chute 8 is the plate 57, pivotally mounted on the pin 58. 45 Its motion is likewise effected by the lever 54 with the aid of the link 60, the length of which can be varied by means of the hand-wheel 59. Before the cutting operation the 50 cheroot bears against the plate 61, rotatable around the pivot 62. The lever 63 forms an extension of the pivot 62 and carries a pin 64, engaging a slot in the link 60, so that on the movement of the same the plate 61 is periodically raised. The blade-spring 65 returns 55 the plate 61 to its vertical position, whereupon it strikes the clip 66, secured to the box 67. The box 67 serves to receive the finished cheroots, being open at its forward end, and 60 in order to prevent the cheroots from falling out the entire cutting device is inclined toward the rear closed wall.

The apparatus operates as follows: The tobacco is led from the tobacco-feedway 11 to 65 the machine, by which a certain quantity is

cut off by the descending knife. In order to give the material a moderate preliminary pressing, the same is pressed against the plate 18, the resistance of which can be regulated by the spring 20. While the knife ascends 70 after cutting off the tobacco, the rammer is forced down by the projection 68 of the cam 16, and thus guides the tobacco between the two guides 12^a and 12^b. The tobacco is now 75 pressed against the table 13, which is at rest, and the bunch is molded between the table and the rammer. After the bunch is molded 80 the rammer remains stationary because the projection 68 has passed the lever 15^d. At the same time the table is set in motion, so that the opening 13' in said table 13 comes under the bunch. At this position the table again remains stationary, while the rammer is again moved by the action of the projection 70 of the cam 16, and the roll is ejected 85 through the opening 13' onto the rolling-apron. When the bunch has left the press, the rammer gradually rises to its highest position, and the table 13 returns to its original position. During this time the wrapper applier has moved forward in order to lead the wrapper to the bunch. The wrapper becomes 90 coated with paste from the descending paste-carrying device, which paste issues through the opening 22' from the groove behind the 95 same. On the container ascending the pawl 29 slips over the teeth of the ratchet-wheel 25 as the end of the lever 26 remains by the action of gravity in contact with the supporting-bolt 28, and consequently describes a 100 smaller arc than the container. On descending, however, the pawl locks the movement of the ratchet-wheel and the drum connected therewith, so that the same turns within the 105 casing and the next groove filled with adhesive comes opposite the opening 22'. In known manner by the movement of the rolling-apron the tobacco roll is provided with its wrapper, so that the finished cheroot leaves the cloth at the rear end of the table 33. At 110 the part 7 of the slideway the cheroot, which is sliding sidewise, is by reason of the shape of the slideway turned around ninety degrees, so that it can pass longitudinally through the chute 8 in front of the cutting device. Then 115 the cheroot bears against the plate 57, which positions it in front of the cutter-jaw. At the same time by the operation of the lever 54 the jaw 46 is set in motion, which moves the cheroot against the plate 61, which on being moved farther turns around its pivot 62. Against the stationary cutting-cheeks the 120 ends of the cheroot are cut off and the plate 61 raised as the pin 64 abuts against the end of the slot in the link 60. On further movement of the cutter-jaw the cheroot is moved under the plate 61 and passes into the box 67. On the return movement of the jaw 46 the plate 61 returns to its vertical position.

Having now described my invention, what 130

I claim, and desire to secure by Letters Patent of the United States, is—

1. In a machine for the production of cheroots and the like, the combination with a 5 pressing device receiving loose tobacco, said pressing device comprising a rammer and a movable table having an opening through which the bunch is free to fall, means for moving said rammer, of a rolling-apron beneath said table, means for applying the wrapper to the bunch, a chute and a cutting device to which the cheroot is led by said chute, said cutting device comprising a cutting-jaw and cheeks on each side of said jaw 15 between which said jaw moves to cut both ends of the cheroot, substantially as described.

2. In a machine for the production of cheroots and the like, the combination with a 20 pressing device receiving loose tobacco, said pressing device comprising guides, table mounted in said guides, a rammer adapted to move between said guides, said table and said rammer being concaved corresponding 25 to the form of the bunch, means for moving said table, means for moving said rammer, of means for applying the wrapper to the bunch, a chute, and a cutting device to which the cheroot is led from said chute and adapted to 30 cut both ends of the cheroot simultaneously, substantially as described.

3. In a machine for the production of cheroots and the like, the combination with a 35 pressing device receiving loose tobacco, said pressing device comprising guides, a table mounted in said guides, a rammer reciprocated between said guides, said table and said rammer being concaved corresponding to the form of the bunch, and said table having an 40 opening through which the bunch is ejected onto the rolling-apron, means for moving the table, means for imparting a two-stage downward movement to the rammer so as first to press the tobacco, and when the table has 45 moved to bring the opening beneath said rammer to force the bunch through said opening, the rolling-apron, means for applying the wrapper to the bunch, a chute, and a cutting device to which the cheroot is 50 brought through said chute, and adapted to cut both ends of the cheroot simultaneously.

4. In a machine for the production of cheroots and the like, the combination with a 55 pressing device receiving loose tobacco, said pressing device comprising a pivoted plate, a spring pressing on said plate and serving to give preliminary pressure to the tobacco, a rammer, a movable table having an opening through which the bunch is free to fall, means 60 for moving said rammer, of a rolling-apron beneath said table, means for applying the wrapper to the bunch, means for supplying paste to the wrapper, a chute and a cutting device to which the cheroot is led by said 65 chute, said cutting device comprising a cut-

ting-jaw, cheeks on each side of said jaw between which said jaw moves to cut both ends of the cheroot and a pivoted plate against which the cheroot is pressed by said jaw, substantially as described.

5. In a machine for the production of cheroots and the like, the combination with a 70 pressing device receiving loose tobacco, said pressing device comprising a moving rammer and a moving table of a rolling-apron beneath said table and receiving the bunch from said table, means for applying the wrapper to the bunch, means for delivering paste to the wrapper, said paste-delivering means comprising a vertically-movable paste-container, 75 a drum rotatably mounted on said container and formed with grooves, and means for rotating said drum to release the paste, a chute, and a cutting device to which the cheroot is led from said chute, substantially as 80 described.

6. In a machine for producing cheroots and the like, the combination with a pressing 85 device of a rolling-apron receiving the bunch from said pressing device, means for applying 90 the wrapper to the bunch, means for supplying paste to the wrapper, said paste-supplying means comprising a paste-containing cylinder, means for reciprocating said cylinder, a grooved drum carried by said cylinder, a 95 ratchet-wheel coaxial with said drum, a pawl turning said ratchet-wheel, a lever to which said pawl is pivoted and means for oscillating said lever, a chute, and a cutting device to which the cheroot is led from said chute, substantially 100 as described.

7. In a machine for the production of cheroots and the like, the combination with a 105 pressing device, of means for applying the wrapper to the bunch, a chute through which the cheroot is fed to the cutting device, and means for cutting the ends of the cheroot simultaneously, said cutting means comprising a cutting-jaw the length of which corresponds to the length of the cheroot, two cheeks 110 between which said jaw is movable, and means for moving said jaw between said cheeks so as to cut both ends of the cheroot, substantially as described.

8. In a machine for the production of cheroots and the like, the combination with a 115 pressing device of means for applying the wrapper to the bunch, a chute through which the cheroot is led to the cutting device and said cutting device comprising a cutting-jaw 120 46, a pivoted plate 62 against which the cheroot is pressed by said jaw, and cheeks between which said jaw is moved to cut the ends of the cheroot simultaneously.

9. In a machine for the production of cheroots and the like, the combination with a 125 pressing device of means for applying the wrapper to the bunch, a chute through which the cheroot is led to the cutting device, said cutting device comprising a cutting-jaw, 130

cheeks between which said jaw is movable, a pivoted plate against which the cheroot is pressed by said jaw, means for imparting a lateral motion to said plate, and means for raising said plate, substantially as described.

10. In a machine for the production of cheroots and the like, the combination with a pressing device, of means for applying a wrapper to the bunch, a chute through which the cheroot is led to the cutting device, said cutting device comprising a cutting-jaw, cheeks between which said jaw is movable, a pivoted plate 62 against which the cheroot is pressed by said jaw, and a plate 57 serving to position the cheroot in front of the cutting-jaw, substantially as described.

11. In a machine for the production of cheroots and the like, the combination with a pressing device of means for applying a wrapper to the bunch, a chute through which the cheroot is led to the cutting device, said cutting device comprising a cutting-jaw and cheeks through which said jaw is moved, a pivoted plate against which the cheroot is pressed by the cutting-jaw, a plate 57 serving to position the cheroot in front of said jaw, a lever serving to move said cutting-jaw, and

means connecting said lever with said plate 57 so as to operate said jaw and said lever from the same point, substantially as described.

12. In a machine for the production of cheroots and the like the combination with a pressing device of means for applying a wrapper to the bunch, a chute leading the cheroot to the cutting device, said cutting device comprising a cutting-jaw, cheeks between which said jaw is moved a pivoted plate 61 against which the cheroot is pressed by said jaw, a plate 57 serving to position the cheroot in front of said jaw, a lever 54 actuating the cutting-jaw, a link 60 connecting said lever with said plate 57, and a lever 63 carrying the plate 61 and having a pin entering a slot in said link 60, in order on the movement of said lever 54 to raise said plate 61 periodically, as described.

In testimony whereof I have signed my name to this specification in the presence of two subscribing witnesses.
